UNITED STATES PATENT OFFICE

GEORGE HENRY ROBERTS, OF ROCK ISLAND, ILLINOIS, ASSIGNOR TO MADISON-KIPP CORPORATION, OF MADISON, WISCONSIN, A CORPORATION OF WISCONSIN

TERMINAL CHECK VALVE

Application filed February 14, 1927. Serial No. 168,219.

The present application is in part a continuation of two prior applications filed by me, namely, check valve, Serial No. 17,498, filed March 23, 1925, and check valve, Serial No. 93,613, filed March 10, 1926.

The invention relates to force feed lubrication, and more particularly to force feed lubrication as applied to steam power plants, for example, steam locomotives.

10 The object of the invention is to produce an improved terminal check valve suited for this service.

Generally stated, a terminal check valve is a check valve interposed between a force feed lubricator and steam passage and designed to open to permit flow of oil from the lubricator to the passage and to close to prevent back-flow from the passage to the lubricator. Various types have heretofore been used, and the present invention is of that known type in which the valve is actuated by a diaphragm urged in valve opening direction by oil pressure and so loaded as to remain closed until the oil pressure reaches a value in excess of pressure in the steam passage.

In prior devices the diaphragm was loaded mechanically, usually by means of an adjustably stressed spring. Such valves were subject to mal-adjustment and to spring failures, either of which would occasionally permit steam to penetrate to the force feed lubricator, with disastrous results.

An important feature of novelty of the present device is that the diaphragm is loaded by fluid under pressure, which is favorable to long life of the diaphragm. Since the fluid pressure is preferably boiler pressure, it follows that the closing tendency of the valve must always be sufficient to maintain the valve closed until oil pressure exceeds any pressure which can exist in the steam passage, at which times oil will flow to the steam passage. Thus the valve is always closed unless oil is actually flowing to the point of use.

The presence of boiler steam in the terminal check valve makes it conveniently possible to by-pass a small portion of the boiler steam to the oil passage leading from the check valve to the steam passage, and thus

steam is fed at all times and particularly when the main throttle is closed and the engine is drifting. This flow of steam prevents the accumulation of water of condensation in the top chamber, which is an incidental advantage, and such flow sweeps the oil through the oil passage and discharges it in atomized form into the steam passage. Thus, when the engine is running under steam, the oil is delivered to the flowing steam in the steam passage in an atomized condition. When the engine is drifting with the throttle closed and there is no steam flow in the steam passage, the oil is swept out of the oil passage and delivered in a spray, instead of being delivered in drops which would readily accumulate and carbonize. Carbonization of the oil occurs in locomotive cylinders when the engine is drifting, because when the engine drifts products of combustion from the smoke box are at times drawn into the cylinder through the exhaust nozzle. Oil sprayed in with a small quantity of steam is less likely to carbonize, and is brought into contact with the moving parts in the valve chest and cylinder so as to lubricate effectively.

This feature of by-passing boiler steam to the oil passage may be used with other types of check valves, and I do not limit this feature of the invention to the particular type of check valve here illustrated.

Various embodiments of the inventive concept are illustrated in the accompanying drawings, in which,

Fig. 1 is a side elevation of a steam chest and cylinder with a portion of the valve gear showing the application of a force feed lubricator and a terminal check valve of the type here described and claimed.

Fig. 2 is an end elevation of the same.

Fig. 3 is a vertical axial section of a commercial embodiment of the terminal check valve.

Fig. 4 is a plan view of the differential diaphragm assembly with a portion broken away to show the spacers.

Fig. 5 is a vertical axial section of a form of the check valve illustrated in application Serial No. 17,498 above mentioned.

valve as illustrated in application Serial No. 93,613, above mentioned.

The casing of the check valve consists of a body 6 and a cap plug 7, threaded at 8 into a projecting annular flange 9 formed on the body. The body 6 is formed with an oil pressure chamber 10 and the cap 7 is formed with a steam pressure chamber 11 which terminate, respectively, at shoulders 12 and 13 formed on the body and cap.

The shouder 12 is formed with an annular groove 14 and the shoulder 13 is formed with an annular groove 15, of the same diameter. A port 16 leads from the space 11 to the groove 15. A port 17 leads from the groove 14 to the oil discharge port 18. Clamped between the shoulders 12 and 13 are the bottom diaphragm 19, the top diaphragm 20 and an interposed spacing ring 21. This ring 21 has on its upper face an annular groove 22 opposed to the groove 15 and on its lower face an annular groove 23 opposed to the groove 14. The grooves 22 and 23 are connected by a port 24. The diaphragms 19 and 20 are provided with small holes 25 and 26 which respectively connect the groove 14 with the groove 23 and the groove 15 with the groove 22. Consequently a by-pass for steam is afforded from the chamber 11 to the port 17 whether the diaphragms 19 and 20 are assembled with the holes 25 or 26 alined or not.

The space between the diaphragms 19 and 20 is vented to atmosphere by way of port 27 in the spacing ring 21 and port 28 in the flange 9. The groove 44 around the outer margin of the spacing ring 21 makes it unnecessary to aline the ports 27 and 28.

A valve carrying member 29 is formed with a threaded upward extension 30 which extends through openings at the center of diaphragms 19 and 20 and also through a spacing member 31 interposed between the middle portions of these diaphragms. A nut 32 threaded on the stem 30 locks the diaphragms and the spacing member together and seals them to the carrier 29.

As is clearly shown in Fig. 3, the spacing ring 21 is beveled alike on its upper and lower face to afford clearance for the movements of the diaphragms. The spacing ring 31, however, is flat on its upper face and beveled or conical on its lower face, the form being such that the area of engagement of the ring with the upper diaphragm 20 is much greater than the area of engagement of the ring with the lower diaphragm 19. It follows that there is a decidedly greater resistance to upward movement of the valve carrying member 29 than there is to its downward movement, partly as a consequence of the resistance of diaphragm 20 to upward flexure. In this way a differential resistance is imparted to the diaphragm structure which gives the valve a bias in favor of a

downward or valve closing movement. The structure is in effect a differential diaphragm and since both diaphragms are the same size is easier to construct and assemble than a conventional differential diaphragm structure requiring two sizes of diaphragms would be. The differential effect is pronounced, a steam pressure of 200 pounds per square inch balancing an oil pressure of as much as 250 pounds per square inch.

Formed on the lower end of the valve carrying member 29 is a threaded tubular extension 33 within which is mounted a headed pin valve 34. This is sustained in position by a coil spring 35 which surrounds it and which engages at its upper end under the head of the pin valve and which is supported at its lower end by an annular cup-shaped nut 36 screwed on to the extension 33. The mounting is such that the pin valve is held upward in engagement with the valve carrier 29 so as to be moved positively in closing direction but is yieldingly supported so that it may accommodate itself to slight irregularities in the location of its seat.

The seat for the pin valve 34 is formed in a ported bushing 37 which is screwed into the body 6 at the bottom of the chamber 10. The port in the seat 37 communicates directly with the port 18 and the port 18 terminates at the end of an extension 38 formed with pipe threads 39.

Oil is delivered to the chamber 10 beneath the diaphragm 19 through a port 40. A union, indicated generally by the reference numeral 41, connects the high pressure oil pipe 42 with the port 40. A pipe threaded opening 43 in the top of the cap 7 admits boiler steam to the space above the diaphragm 11. The ports 27 and 28 are provided merely to vent the space between the two diaphragms and indicate leakage, should this occur.

The check valve above described may be used as illustrated in Figs. 1 and 2, in which 49 represents a locomotive boiler, 50 the main steam pipe controlled by the main throttle and leading to a steam chest 51 which contains a distributing valve mechanism for the steam cylinder 52. 53 is a portion of the valve stem guide and 54 is a combination lever forming a portion of a Walschaert or similar valve gear. The locomotive parts just mentioned are chosen as typical and it will be understood that the combination lever is representative of any reciprocating part from which motion can conveniently be derived.

Lever 54 is connected by a link 55 with the lower end of a swinging drive arm 56 fixed on the oscillating drive shaft 57 of a force feed lubricator, indicated generally by the numeral 58 supplied to the oil tank. A pumping unit or units are mounted inside

the tank, as shown for example in Patent No. 1,522,673, Coles, January 13, 1925.

Tank 58 is supported by a bracket 59 on a portion of the steam chest 51 and the lubricator delivers oil under pressure through one or more discharge pipes, one of which is indicated by the numeral 42, which is the oil pipe leading to the terminal check valve.

The threaded extension 38 of the check valve already described is screwed into a fitting 60, commonly called a quill, which projects into the steam pipe 50 and which is designed to discharge oil received from the passage 18 within the steam pipe 50. 61 is a live steam pipe connected directly with the boiler so that it receives boiler steam whether the main throttle which supplies steam to the steam pipe 50 is opened or closed. The pipe 61 is connected as shown in Fig. 1 to the threaded opening 43 in the cap 7.

Thus when the boiler is under steam the diaphragm 20 is constantly subject to boiler pressure acting downwardly on the upper face of the diaphragm. Whenever the engine is in motion the diaphragm 19 is subject to the pressure developed by the lubricator pump acting upward. It follows that only when oil pressure predominates over boiler pressure the valve 34 will open. The amount by which the oil pressure must predominate depends on the differential characteristic of the diaphragm structure and may be varied by various obvious changes in the design of the diaphragm structure.

In Fig. 5 a simpler embodiment of the invention is illustrated.

In this structure the casing of the device consists of a sleeve 71 threaded at its ends to receive a top cap 72 and a bottom cap 73. The top cap 72 is formed with a steam inlet connection 74 which leads to a steam chamber 75 above a laminated diaphragm 76. The diaphragm 76 is clamped between a shoulder within cap 72 and a sealing ring 77 which is seated on the end of the sleeve 71. The diaphragm 76 is connected at its center by a cap screw 78 to the thrust block 79.

The bottom cap 73 is formed with an oil inlet connection 81 which leads to the oil pressure chamber 82 beneath the laminated diaphragm 83. This diaphragm is clamped between a shoulder in the bottom cap 73 and a sealing ring 84 which abuts against the end of the sleeve 71. The middle portion of the diaphragm 83 is clamped to a thrust block 85 which is in thrust engagement with the thrust block 79. The connection between the diaphragm and the thrust block is made by means of a threaded plug 86 which is formed with a central aperture to receive and guide a pin valve 87. This valve is formed with an enlargement or head at its upper end which works in a recess formed in the thrust member 85 and threaded plug 86. A coil spring 88 surrounds the pin valve 87 and seats on

the plug 86 and against the under side of the head of the pin valve, holding this upward in engagement with the thrust block 85.

Pin valve 87 coacts with the seat in a valve seat bushing 89 which is screw threaded into the bottom cap 73. The valve 87 thus controls the port through the bushing 89 and consequently controls the discharge of oil through the port 91. The space between the diaphragms 76 and 83 is vented to atmosphere at 92. In this device boiler steam is admitted at 74, oil from the force feed lubricator is admitted at 81 and this oil is discharged through the port 91 to the steam passage. The device is connected in the same manner and operates in substantially the same manner as that shown in Fig. 3. The differences are that no steam is by-passed from the space 75 to the passage 91, and the diaphragms are not connected but are merely in thrust relation with each other. There is a differential action between the upper and lower diaphragms, the lower diaphragm seating against a reduced neck on the member 85 so that it has a larger unsupported area than the upper diaphragm 76 which seats over the entire area of the member 79.

In Fig. 6 another modification of the invention is illustrated. In this instance the body of the device consists of a casing member 95 into which is threaded a cap plug 96. The diaphragm structure consists of a lower laminated diaphragm 97, an upper laminated diaphragm 98, and a conical spacer 99 which like the spacer of Fig. 3 has a smaller area of contact with the lower diaphragm than with the upper diaphragm so as to produce the differential effect already described. The spacer 99 is connected with the upper diaphragm 98 by a cap screw 100 and with the lower diaphragm 97 by a threaded plug 101 which guides a pin valve 102 having a head at its upper end. The head of the pin valve works in a recess formed in the plug 101 and is held in its upward position by a spring 103. The valve coacts with a port in the seat bushing 104 screwed into the body 95.

Between the margins of the two diaphragms is a spacer structure including an annular member 105 having a circumferential groove or channel 106 on its outer face. The purpose of this channel is to secure connection of a through port 107 in the spacing member with the vent port 108 in the body 95. The lower diaphragm 97 seats on a shoulder in the body 95 and the annular member 105 seats on the diaphragm. The upper surface of the member 105 is beveled to receive a beveled sealing ring 109 which fits closely within the body 95 and which may be slightly deformed so as to expand into sealing contact as a result of its wedging engagement with the spacer 105. The dia-

phragm 98 seats on the upper face of the ring 109 and is clamped thereagainst by an annular face 110 on the cap plug 96.

Formed in the body 95 and outside the face 110 is a channel 111 which communicates with the space 112 above diaphragm 98 by means of ports 113. Channel 111 also communicates by means of port 114 with the oil discharge port 115 to which the port in 10 valve seat 104 leads.

Oil is supplied through the port 116 to the space 117 beneath the diaphragm 97, and under the control of the pin valve 102 discharges through the port 115. Steam at 15 boiler pressure is delivered through port 118 to the space 112 above the diaphragm 98. A portion of the steam is by-passed through the ports 113, 114 and 115 to mix with the oil which has passed the valve.

20 It will be observed that the structure of Fig. 6 is functionally identical with the structure of Fig. 3, including as it does, the differential diaphragm effect, the by-passing of the steam to the oil discharge port, and similar features.

25 The structures of Figs. 5 and 6 are illustrated to establish the identity of subject matter here claimed with the subject matter of the two original applications above identified.

30 While the structures illustrated and described, and particularly that shown in Fig. 3, are preferred, for practical reasons, I recognize that the invention is susceptible 35 of embodiment in specifically different forms. The prime advantage is the elimination of the loading spring and the substitution of fluid pressure, usually steam pressure and preferably, but not necessarily, 40 boiler pressure. Any source of adequate pressure which is always charged when the engine is in motion, might be used, so far as the broadest aspect of the invention is concerned.

45 Unless the source of loading pressure is substantially higher than the pressure in the passage to which the oil is to be delivered, the valve should be given a bias in a closing direction, and this effect may be produced in 50 various ways. The most convenient is to make use of some differential diaphragm mechanism. By differential diaphragm mechanism, I mean one in which the valve will not open until the oil pressure acting 55 in an opening direction materially exceeds the fluid pressure acting in a closing direction. It is immaterial, so far as the broad aspects of the invention are concerned, whether this effect is secured by the use of 60 an asymmetric spacing member, as described, or by the use of conventional differential diaphragms.

What is claimed is,—

1. The combination of a steam motor; a 65 steam line for supplying steam thereto; an

oil forcing pump; a valve; oil conducting connections from the pump to the valve and from the valve to a steam space associated with said motor; an abutment mechanism connected with said valve to operate the same; means for subjecting said abutment mechanism to the pressure of oil pump discharge acting in a valve opening direction; and means for subjecting said abutment to an approximately constant fluid pressure acting 70 in a valve closing direction. 75

2. The combination of a steam motor; means for supplying steam thereto; an oil forcing pump; a valve; oil conducting connections from the pump to the valve and from the valve to a steam space associated with the motor; an abutment mechanism connected with said valve to operate the same; and connections whereby said abutment is subject in valve closing direction to supply steam pressure and in valve opening direction to the pressure of oil pump discharge, the parts being so proportioned and arranged that oil pressure opens the valve in opposition to supply steam pressure in the ordinary 80 operation of the device. 85

3. The combination of a steam motor; means for supplying steam thereto; an oil forcing pump; a valve; oil conducting connections from the pump to the valve and from the valve to a steam space associated with the motor; an abutment mechanism connected with said valve to operate the same and having a bias in a valve closing direction; and connections whereby said abutment 90 is subject in valve closing direction to supply steam pressure and in valve opening direction to the pressure of oil pump discharge, the parts being so proportioned and arranged that oil pressure opens the valve in opposition to supply steam pressure in the ordinary 95 operation of the device. 100

4. The combination of a steam motor; a main steam line for supplying steam thereto; an oil forcing pump; a valve; oil conducting connections from the pump to the valve and from the valve to a steam space associated with the motor; an abutment mechanism connected with said valve to operate the same; means for subjecting said abutment mechanism to the pressure of oil pump discharge acting in valve opening direction; and means independent of the main steam line for subjecting said abutment mechanism to supply steam pressure acting in valve closing direction. 110 115

5. The combination of a steam motor; means for supplying steam thereto; an oil forcing pump; a valve; oil conducting connections from the pump to the valve and from the valve to a steam space associated with the motor; a diaphragm structure connected with said valve to actuate the same; connections whereby said diaphragm structure is subject in valve closing direction to 120 125 130

- live steam pressure and in valve opening direction to the pressure of oil pump discharge; and means serving to impart to said diaphragm structure a differential characteristic whereby the valve is held closed until oil pressure predominates in a substantial degree.
6. The combination of a steam motor; means for supplying steam thereto; an oil forcing pump; a valve; oil conducting connections from the pump to the valve and from the valve to a steam space associated with the motor; a pair of diaphragms connected to actuate said valve, one subject to supply steam pressure acting to close the valve and the other subject to oil pump discharge pressure acting to open the valve; and means associated with the connections between the diaphragms and valves and serving to impart a differential effect whereby the valve is opened only when oil pressure predominates.
7. The combination of a steam motor; means for supporting steam thereto; an oil forcing pump; a valve; oil conducting connections from the pump to the valve and from the valve to a steam space associated with the motor; a pair of diaphragms connected to actuate said valve, one subject to supply steam pressure acting to close the valve and the other subject to oil pump discharge pressure acting to open the valve; and a connecting spacer between said diaphragms, said spacer having a larger area of contact with the steam pressure diaphragm than with the oil pressure diaphragm.
8. The combination of a steam motor; means for delivering steam thereto; an oil forcing pump; a valve; oil conducting connections from said pump to said valve and from said valve to a steam space associated with the motor; means responsive to oil pressure for opening said valve; and a connection arranged to deliver live steam to the oil connection between said valve and steam space.
9. The combination of a steam motor; means for supplying steam thereto; an oil forcing pump; a valve; oil conducting connections from the pump to the valve and from the valve to a steam space associated with the motor; an abutment mechanism connected with said valve to operate the same; connections whereby said abutment is subject in valve closing direction to live steam at supply pressure and in valve opening direction to the pressure of oil pump discharge; and a bleed connection leading live steam from adjacent said abutment to the oil connection between said valve and steam space.
10. The combination of a steam motor; a main steam line for supplying steam thereto; an oil forcing pump; a valve; oil conducting connections from said pump to said valve and from said valve to a steam space associated with the motor; means responsive to oil pressure for opening said valve; and

means independent of said main steam connections for delivering live steam to said oil connections between said valve and steam space.

11. The combination of a steam motor; a main steam supply line leading thereto; an oil forcing pump; a valve; oil conducting connections from the pump to the valve and from the valve to a steam space associated with the motor; an abutment mechanism connected with said valve to operate the same; means for subjecting said abutment mechanism to the pressure of oil pump discharge acting in a valve opening direction; a connection independent of the main steam supply line serving to direct supply steam pressure against said abutment mechanism in valve closing direction; and a bleed connection leading from the last-named connection to the oil connection between the valve and said steam space.

12. In a terminal check valve the combination of a sectional body; a diaphragm structure clamped between the parts of said body and dividing it into a fluid pressure chamber and an oil pressure chamber; means for conducting pressure fluid to the fluid pressure chamber; means for conducting oil under pressure to the oil pressure chamber; a valve seat controlling a discharge passage leading from the oil pressure chamber; a valve operatively connected with said diaphragm structure and arranged to close against said seat when the total effective fluid pressure on the diaphragm structure exceeds the total effective oil pressure thereon; and means for discharging a pressure fluid from the fluid pressure chamber to the discharge passage at a limited rate.

13. In a terminal check valve, the combination of a sectional body; a diaphragm structure clamped between the parts of said body and including two diaphragms with a center spacing means arranged to cause the diaphragms to move in unison and with a margin spacing means arranged to sustain and seal the peripheries of the diaphragms, said diaphragm structure dividing the interior of the casing into a fluid pressure chamber and an oil pressure chamber; a valve seat controlling a discharge passage leading from the oil pressure chamber; and a valve operatively connected with said diaphragm structure and arranged to close against said seat when the total effective fluid pressure on the diaphragm structure exceeds the total effective oil pressure thereon.

14. In a terminal check valve, the combination of a sectional body; a diaphragm structure clamped between the parts of said body and including two diaphragms with a center spacing means having a larger area of engagement with one diaphragm than with the other, arranged to cause the diaphragms to move in unison and with a margin spacing means arranged to sustain and seal the peripheries of

the diaphragms, said diaphragm structure dividing the interior of the casing into a fluid pressure chamber and an oil pressure chamber; a valve seat controlling a discharge passage leading from the oil pressure chamber; and a valve operatively connected with said diaphragm structure and arranged to close against said seat when the total effective fluid pressure on the diaphragm structure exceeds the total effective oil pressure thereon.

15. In a terminal check valve, the combination of a sectional body; a diaphragm structure clamped between the parts of said body and including two diaphragms with a center spacing means arranged to cause the diaphragms to move in unison and with a marginal spacing means arranged to sustain and seal the peripheries of the diaphragms, said diaphragm structure dividing the interior of the casing into a fluid pressure chamber and an oil pressure chamber; a valve seat controlling a discharge passage leading from the oil pressure chamber; a valve operatively connected with said diaphragm structure and arranged to close against said seat when the total effective fluid pressure on the diaphragm structure exceeds the total effective oil pressure thereon; and means for discharging pressure fluid from the fluid pressure chamber to the discharge passage at a limited rate.

16. The combination of a steam motor; means for supplying steam thereto; an oil forcing pump; a valve; oil conducting connections from the pump to the valve and from the valve to a steam space associated with the motor; a pair of spaced diaphragms connected to operate said valve, one subject to supply steam pressure acting to close the valve and the other subject to oil pump discharge pressure acting to open the valve; and means for venting the space between said diaphragm arranged to indicate leakage of oil or steam.

17. A valve for a force feed lubricator system, the valve controlling the discharge of lubricant under the pressure for delivery into a steam cylinder or the like comprising, a valve body formed with an oil chamber having a valve controlled restricted discharge port, and a steam chamber for connection with a steam cylinder to which the lubricant is to be delivered, and a valve for closing said port exposed to relatively opposing pressures in said lubricant and steam chambers with the pressure in said steam chamber normally prevailing to close the valve until the lubricant pressure rises to a point in excess of the steam pressure in the cylinder.

18. A valve for a force feed lubricator system, the valve controlling the discharge of lubricant under the pressure for delivery into a steam cylinder or the like comprising, a valve body forming an oil chamber having a valve controlled restricted discharge port, and a steam chamber for connection with a steam cylinder to which the lubricant is to be

delivered, a diaphragm secured within the body exposed to opposing pressures in said chambers, and a valve for closing said port fixed to said diaphragm, the pressure in said steam chamber normally prevailing on said diaphragm to close the valve until the lubricant pressure rises to a point in excess of the steam pressure in the cylinder.

19. In a terminal check valve, the combination of a body; a diaphragm structure dividing said body into a fluid pressure chamber and an oil pressure chamber; means for conducting fluid under pressure to the fluid pressure chamber to establish pressure therein; means for conducting oil under pressure to the oil pressure chamber; a valve seat controlling a discharge passage leading from the oil pressure chamber; a valve operatively connected with said diaphragm structure and arranged to close against said seat; and means for discharging to the discharge passage a portion of the pressure fluid which acts to establish pressure in the pressure chamber.

20. In a terminal check valve, the combination of a sectional body; a diaphragm structure clamped between the parts of said body and including two diaphragms with a center spacing means arranged to cause the diaphragms to move in unison and with a marginal spacing means arranged to sustain and seal the peripheries of the diaphragms, said diaphragm structure dividing the interior of the body into a fluid pressure chamber and an oil pressure chamber; a valve seat controlling a discharge passage leading from the oil pressure chamber; a valve operatively connected with said diaphragm structure and arranged to close against said seat; means for conducting oil under pressure to the oil pressure chamber; means for conducting fluid under pressure to the fluid pressure chamber; and means for discharging a portion of the last named fluid to said discharge passage.

In testimony whereof I have signed my name to this specification.

GEORGE HENRY ROBERTS.
